(57) **CLAIM**

The ornamental design for a stage pin electrical connector, as shown.

DESCRIPTION

FIG. 1 is a top, left and front perspective view of a stage pin electrical connector showing our new design;
FIG. 2 is a bottom, left and rear perspective view thereof;
FIG. 3 is a front elevation view thereof;
FIG. 4 is a rear elevation view thereof;
FIG. 5 is a left side elevation view thereof;
FIG. 6 is a right side elevation view thereof;
FIG. 7 is a top plan view thereof; and,
FIG. 8 is a bottom plan view thereof.

The broken line in the figure drawings is included for the purpose of illustrating environment and forms no part of the claimed design.
